UNITED STATES PATENT OFFICE.

CHARLES G. BODMAN, OF DE KALB, ILLINOIS.

BARBED FENCE-WIRE.

SPECIFICATION forming part of Letters Patent No. 262,200, dated August 8, 1882.

Application filed August 2, 1879.

To all whom it may concern:

Be it known that I, CHARLES G. BODMAN, of De Kalb, De Kalb county, State of Illinois, have invented a new and useful Improvement 5 in Barbed Fence-Wire, of which the following is a full description, reference being had to the accompanying drawings, in which—

Figure 1 is a perspective view showing one form of my improved barb. Fig. 2 is a cross- 10 section of the same. Fig. 3 is a perspective showing a second form of my barb. Fig. 4 is a cross-section of the same.

This invention relates to improvements in 15 that class of barbed-wire fences composed of twisted wires and four-pointed barbs; and it consists essentially in the combination, with 20 the twisted strands, of four-pointed barbs, each barb consisting of two barb-pieces, both 25 rectangularly bent, with a loop or eye at the middle, and placed with one prong of each 30 piece resting in the eye of the other, and with 35 one cable-strand passing through each eye, as 40 will be more fully hereinafter described in detail.

25 In the drawings, *a b* represent the two strands of a fence-wire twisted together, the barbs being applied while these wires are being twisted.

I have shown two forms of my barb, differ- 30 ing slightly one from the other in the details of bending, but both bent and applied to the main wire so as to accomplish the desired re- 35 sult in substantially the same manner. The first form is shown in Figs. 1 and 2. This 40 barb is composed of two pieces of wire, *c d*. The piece *c* is bent once around the strand *a*, 45 forming a loop, *f*, at the center, its two ends, *e e'*, standing at right angles to each other and 50 forming two prongs of the complete barb. The other piece, *d*, is bent once around the strand *b*, its two ends, *h h'*, standing at right angles 55 to each other, and a loop, *g*, being formed at the center. The end *e'* of the piece *c* passes 60 through the loop *g*, and the end *h'* of the piece 65 *d* passes through the loop *f*. Thus not any 70 of the prongs of the barb are wrapped around 75 the outside of either of the strands *a b* and 80 left so that they can be unwound therefrom 85 either wholly or partly; but two of the points, 90 *e* and *h*, pass out from between the two strands 95 *a b*, while the other two pass one through the

loop *f* and the other through the loop *g*. In 55 the form which I am now describing the two 60 points *e h* are side by side and upon the same 65 side of the barb. The second form is repre- 70 sented in Figs. 3 and 4, and the same letters 75 are used as have been used to represent and 80 describe the first form. The only difference 85 between these two forms is that the point *h* 90 passes out from between the two strands *a b* 95 upon the back side of the barb, instead of upon 100 the front, as in the first form. This is pro- 105 duced by carrying that part of the wire which 110 forms the loop *g* first up over the front and 115 then down behind the point *e'*, instead of first 120 behind and then down in front thereof, as is 125 done in the first form.

130 My invention has many advantages. Each 135 point or prong of the barb is held and sup- 140 ported either by a loop or by and between the 145 two strands *a b*, and as none of the points or 150 prongs are upon the outside of the main wires 155 they cannot be unwound, which frequently hap- 160 pens when any of the prongs are wound upon 165 the outside of the main wires, both in hand- 170 ing rolls of wire before the same is applied 175 to posts and after the same has been applied. 180 A smaller wire can be used for the barbs than 185 when the barbs or some of them are on the 190 outside of the main wire, as the several prongs 195 are not held in position solely by the strength 200 of the barb-wire. The barb cannot rotate on 205 the main wire; neither can there be any lateral 210 or other displacement which will affect the 215 efficiency of the barb. Again, the two strands 220 of the main wire are not so bound together by 225 the barbs as to interfere with the expansion 230 and contraction of the strands of the main 235 wire, and this allows an equal tension on the 240 several strands.

245 What I claim as new, and desire to secure 250 by Letters Patent, is as follows:

1. The combination, with the twisted strands, 255 of four-pointed barbs, each barb consisting of 260 two barbed pieces, both rectangularly bent, 265 with a loop or eye at the middle, and placed 270 with one prong of each piece resting in the 275 eye of the other, and with one cable-strand 280 passing through each eye, substantially as set 285 forth.

2. A barbed fence-wire consisting of the 290 strands *a b*, twisted together, and the four- 295

pointed barbs, each composed of the two wires *c d*, the wire *c* being bent around the strand *a*, so as to form the loop *f* at the center, and so that the two prongs *e e'* stand at right angles to each other, and the piece *d* being bent around the strand *b*, so as to form a loop, *g*, at the center, and so that the two prongs *h h'* stand at right angles, or nearly so, to each other, the prong *e'* passing through loop *g* and the prong *h'* passing through the loop *f*, and the two

prongs *e h* passing out from between the two twisted strands *a b*, the prongs *e h* being in parallel lines and the prongs *e' h'* being in parallel lines at right angles to lines of the said prongs *e h*, as specified.

CHARLES G. BODMAN.
